FLUSHING MECHANISM FOR TOILET TANKS

Julian L. Mason and Glenn L. McNabb,
Gastonia, N. C.

Application April 8, 1939, Serial No. 266,783

4 Claims. (Cl. 4—57)

This invention relates to a flushing mechanism for water closets. More specifically it relates to an improved tripping means for the tank ball, which will insure proper setting of the flushing valve or tank ball and thus eliminate water leakage due to sticking of the tank ball occurring after a flushing operation. Heretofore, many types of tripping mechanisms have been employed the structure of which has been such that the moving parts will become frictionally engaged with the stationary supporting member and thereby prevent the flushing valve from becoming properly closed. This occasions much loss in water and much annoyance due to the cause or necessity of having to frequently reposition the parts in the apparatus.

It is, therefore, an object of this invention to provide a tripping mechanism for a valve or tank ball in a water closet, comprising an operating shaft rotatably mounted in the sidewall of the tank and a flexible connection, unsupported throughout its length, disposed between said shaft and said valve whereby the valve can be operated from the shaft with a minimum frictional resistance.

It is a further object of this invention to provide a tripping mechanism of the class described with a handle on the outer end of an operating shaft which may be rotated in either direction to trip the valve, with means associated therewith for limiting the amount of rotation which is imparted to said shaft. This limiting means prevents the shaft from making a complete revolution which, if done, would cause the flexible connection to hang and prevent the valve from becoming properly seated after flushing.

The present invention comprises a simple and efficient method of flushing water closets. It is inexpensive to manufacture, easy to operate and very efficient in operation, all of which constitute desirable features in the apparatus.

Some of the objects of the invention having been stated, other objects will appear as the description proceeds when taken in connection with the accompanying drawings, in which—

Figure 1 is a front elevation of a water closet with certain portions thereof shown in section to disclose the invention;

Figure 2 is a vertical sectional view taken along the line 2—2 in Figure 1;

Figure 3 is an isometric view of the invention apart from the water closet.

Referring more specifically to the drawings, the numeral 10 denotes a conventional toilet tank having an intake pipe 11, said intake pipe pene-

trating its bottom and which has secured to the upper end thereof an intake valve 12. Pivoted to this valve as at 14 is an arm 15 which extends upwardly and laterally within the tank, and has on its free end a suitable hollow float ball 16. 5 The lever 15 has pivoted intermediate its ends as at 17, a valve piston 18, which is raised and lowered, depending upon the level of the water 19. Of course when the water level falls the ball 16 will likewise fall, which, in turn, will move 10 the piston 18 downwardly to allow water to flow into the tank. The above parts are conventional.

Disposed in the bottom of the tank 10 is a discharge conduit 25 having a valve seat 26 integral with the upper end thereof. This conduit 15 penetrates the bottom of the tank and is secured thereto by means of a suitable nut 27 threadably secured on the lower end thereof. Washers 29 and 30 are placed below and above the bottom of the tank to insure that the connection at this point will be water tight. The lower end of the conduit 25 is secured to another conduit 32 which empties into a bowl 33, said bowl having pivoted thereto as at 34 a conventional seat 35 and a cover 36. 20

The conduit 25 has a leading from the upper side thereof, a passageway 38 which communicates with the lower end of overflow pipe 39. Also disposed around the conduit, directly beneath the valve seat 26 and above the washer 30, 30 is an annular ring member 40, having integral therewith an L-shaped arm 41, the upper end of which has pivoted as at 42, the intermediate portion of a lever 43. The right-hand end of this lever has adjustably secured in the end thereof, 35 a screw 44 and the lower end of this screw is threadedly secured in the upper end of a tank ball 45. In order to lock the screw in fixed position relative to the lever 43, a lock nut 46 is provided. Likewise a lock nut 47 is provided to lock 40 the tank ball in fixed position relative to the screw 44. This tank ball has an inverted frustoconical portion on the lower side thereof, which is adapted to fit upon the valve seat 26 and prevent the water from escaping downwardly 45 through conduit 25 and into bowl 33.

It will also be noted that the lever 43 extends a substantial distance to the left of pivot point 42 in Figures 1 and 3. The purpose of providing this extension is to counterbalance the weight of 50 the tank ball 45. Also it will be noted by referring to these same figures, that the lever 43 is mounted in a suitable slot 41a in arm 41. The depth of this slot is such that the bottom thereof will act as a stop and prevent farther counter- 55

clockwise rotation of the lever 43 when it is rotated to dotted line position as shown in Figure 1.

At a point between the pivot 42 and the screw 44 a hole 50 is provided in lever 43 which hole 5 is penetrated by a hook on the lower end of a link 51. This link 51 extends upwardly and has a hook on the upper end thereof which is connected to the lower end of a short link 52 and the upper end of link 52 penetrates a hole 53 10 in the lower end of a downwardly extending lever 54. Lever 54 is adapted to be fixed secured on a shaft 55 by any suitable means such as a cotter pin 56. Shaft 55 extends to the exterior of the tank and has an operating handle 57 fixed 15 thereon which handle may be oscillated either in a clockwise or a counterclockwise manner in Figure 1, when it is desired to flush the tank 10. The parts are shown in dotted line position in Figure 1, when the tripping mechanism has been 20 operated.

Shaft 55 is rotatably mounted in a suitable bushing 60, said bushing being mounted in the sidewall of the tank. This bushing has an enlarged head on the exterior of the tank and a 25 threaded portion on the interior, which threaded portion has secured thereon a nut 61. The tank 10 is covered by a suitable cap 63.

By providing a simple tripping mechanism as shown, it is possible to flush the tank with the 30 greatest of ease, and without any likelihood of the parts becoming hung. Also by providing the lock nuts 46 and 47, the tank ball 45 can be properly adjusted relative to the lever 43 and seat 26 to insure that the proper seating will be 35 effected.

The arm 41 may be cast integrally with member 25 if desired, instead of its being a separate piece.

In the drawings and specification, there has 40 been set forth a preferred embodiment of the invention, and although specific terms have been employed, they are used in a generic and descriptive sense only and not for the purposes of limitation, the scope of the invention being set forth 45 in the appended claims.

We claim:

1. In a tank for water closets provided with a 50 vertically disposed discharge pipe penetrating the bottom of the tank and having an open upper end adapted to receive a tank ball for normally closing the open upper end of the discharge pipe, a rigid stem connected to the upper surface of the tank ball, a lever rigidly connected at one end to the upper end of the rigid stem, 55 a member projecting horizontally and then upwardly from said pipe, a pivotal connection between an intermediate portion of the lever and

the upper end of the member projecting from said pipe, an operating handle disposed on the exterior of the sidewall of the tank and having a shaft rotatably penetrating the sidewall of the tank, a second lever rigidly mounted on the inner 5 end of the shaft, and a flexible connection between the two levers.

2. In a water closet tank having a vertically disposed discharge pipe penetrating the bottom of the tank and having an open upper end adapted 10 to receive a tank ball for closing the same, a stem rigidly secured to the tank ball and extending upwardly, a member associated with said pipe and extending horizontally and then upwardly in the tank, a lever pivotally connected 15 intermediate its ends to the upper end of the member, a rigid connection between the lever and the stem, an operating shaft penetrating the sidewall of the tank, and a flexible connection between the shaft and the lever member for 20 raising the tank ball from its seat.

3. Tank ball supporting and operating means for water closets, comprising a member having one end rigidly connected to the tank ball, means for pivotally mounting the member substantially 25 at its center of gravity, operating means extending from the exterior of the tank to the interior thereof, and a flexible connection between the operating means and the end of the member connected to the tank ball. 30

4. In a water closet having a tank provided with a vertically disposed discharge pipe opening into and through the bottom of the tank, an annular member surrounding the pipe and a nut threadably mounted on the pipe for securing the 35 pipe in position and holding said annular member in position, said annular member having a horizontal portion and upwardly projecting portion, said arm being forked at its upper end, an elongated member pivotally mounted intermediate 40 its ends in said fork at a point which is substantially the center of gravity of said pivoted member, means for rigidly supporting a tank ball on one end of the pivoted member for normally closing the upper end of the pipe, an operating 45 shaft penetrating the sidewall of the tank and having a crank on its inner end, a jointed connection between said crank and said pivoted member whereby rotation of said shaft will raise the end of the pivoted member to which the tank 50 ball is attached to allow the contents of the tank to discharge through said pipe, whereupon the tank ball will be guided by said pivoted member into the open upper end of said pipe.

JULIAN L. MASON.
